UNITED STATES PATENT OFFICE

CHARLES A. BABB, OF MEADVILLE, MISSOURI, ASSIGNOR OF ONE-HALF TO
OSCAR T. BOTT, OF SAME PLACE.

WAGON.

SPECIFICATION forming part of Letters Patent No. 671,364, dated April 2, 1901.

Application filed January 23, 1901. Serial No. 44,454. (No model.)

To all whom it may concern:

Be it known that I, CHARLES A. BABB, a citizen of the United States, residing at Meadville, in the county of Linn and State of Missouri, have invented new and useful Improvements in Wagons, of which the following is a specification.

This invention relates to wagons, it being in the nature of a combination-vehicle, as by slight and quick changes it can be made into, first, an ordinary farm-wagon for hauling grain, lumber, and many other articles which may be transported in a wagon of the ordinary kind; second, a stock-wagon for hauling hogs, sheep, poultry, &c.; third, into a hay wagon or rack, and, finally, into a wagon peculiarly adapted for carrying corn-fodder, and the wagon is equally strong without being unduly heavy in its several different adjustments.

The improved wagon includes in its construction a wagon-box having apertures in its opposite sides, cross-bars removably fitted in said apertures, and side members detachably connected to the cross-bars. When these cross-bars are in horizontal position and are disposed transversely of the box and when the side members are sustained upon the outer ends of the cross-bars, a hay rack or wagon is formed, and I prefer in this construction to employ ladders or uprights of usual type at the opposite ends of the rack. The side members just alluded to are preferably made up of a plurality of body-pieces united by longitudinal slats or strips running the entire length of the wagon-box, and said body-pieces having extensions or legs, which when the wagon is to be used for hauling stock are fitted into the grooves or guideways in the upright slatted side members, one of these gates being at the middle of the wagon, so that the stock-carrying portion thereof can be separated into compartments and different kinds of animals carried without possibility of the same quarreling among themselves, the middle gate also materially strengthening the wagon. By removing all the detachable parts

the box can be used as an ordinary farm-wagon, and I prefer to make the box imperforate, as the absence of holes prevents the escape of grain when the same is being hauled either in bulk or bag.

The invention is not limited to the construction just briefly outlined, for certain features may be materially modified within the scope of the accompanying claims, and it is represented in one simple and convenient embodiment thereof in the accompanying drawings, wherein—

Figure 1 is a plan view of the wagon with the parts arranged to form a hay-rack. Fig. 2 is a longitudinal central section of the same. Fig. 3 is a plan view of the wagon in the form of a stock-rack with the several gates in position. Fig. 4 is a plan view of one of the side members in the position it occupies when forming part of the hay-rack. Fig. 5 is an elevation of one of the cross-bars or standards. Fig. 6 is a plan view of the wagon-box with the several parts detached therefrom. Fig. 7 is a perspective view of the rear ladder. Fig. 8 is a transverse section of the wagon arranged for carrying hay or the like. Fig. 9 is a similar view with the parts in position to haul stock. Fig. 10 is a perspective view of a post. Figs. 11 and 12 are elevations of two bolts.

Like characters designate like parts in all the figures of the drawings.

The improved wagon includes in its construction a box or body, as 12, which may be of any suitable size and made from materials usually employed in this class of work. I have not deemed it necessary to indicate the manner of mounting the box on the running-gear, for this may be as usual. The sides, front, and bottom of the box 12 I prefer to make imperforate, as where holes are present they afford a means of escape of loose grain or grain in bags that is being hauled.

I will first describe the wagon with its parts arranged for carrying hay or analogous material.

The wagon-box has interiorly thereof, on its opposite sides, vertically-disposed strips, as 13. These strips are arranged in pairs and are suitably secured to the inner faces of the

wagon-box sides, and they form guides or grooves, as 14, to receive certain of the detachable parts. There are four pairs of strips on each side, and the respective pairs are in 5 alinement transversely of the wagon-box. The upper ends of these strips are substantially flush with the upper edges of the sides, and the sides of the box have apertures or notches 14' to receive the cross-bars or standards 15, of any desired number, though four are shown, the notches being of such a depth that the upper faces of the standards will be substantially flush with the upper edges of the sides. The cross-bars have their opposite 15 ends squared or shouldered to fit snugly against the inner faces of the sides, and they further have arms, as 17, projecting outward and at a slight slant upward from the wagon-box, said arms serving to sustain the side 20 members 18. Said side members are of substantially duplicate construction, and they include a plurality of approximately equidistantly spaced body members or pieces, as 19, resting on the arms 17 and united by the slats 25 or boards. These body members 19 have legs or extensions 21, the inner ends of which are freely fitted between loops or clips, as 22, secured to the standards or cross-bars 15, said loops being of substantially inverted-U shape 30 and they being arranged in pairs on the standards, one loop of each standard being adapted to receive a leg on one body member, while the other loop receives the oppositely-disposed leg of the other body member. The 35 upper sides of the standards are angularly shaped to snugly receive the correspondingly-formed under faces of the side members 18, the latter being detachably but rigidly held in place by bolts, as 23, having spring-pins at 40 their lower ends. By removing the pins the bolts can be taken from their holes, and by sliding the side members 18 outwardly a very short distance or until the extensions 21 are clear of the loops 22 the side members can be 45 lifted clear of the standards.

When using the vehicle as a hay-wagon, I provide ladders or uprights at the front and rear of the wagon to confine the hay at these places, the ladders being denoted, respectively, by 24 and 25 and having feet or bases, as 26, said feet having reduced portions, as 27, fitted in grooves, as 28, near the opposite ends of the box. The grooves just mentioned are formed by the inner ones of the end pairs 50 of strips 13 and adjacent strips, as 29. The ladders have near their feet the projections 30, adjacent to and under the front and rear standards or cross-bars 15, so that when the parts are assembled to form a hay-wagon said 60 standards will prevent the ladders from being pulled from place. The load of hay is held down by the usual pole (not shown) connected with the front ladder, and the opposite end of which can be placed under the pin 31. Said 65 pin 31 is vertically adjustable, it being adapted to be placed in any one of the vertical row

of holes 31', and it is connected by a chain or equivalent device, as 31", with the rear ladder.

By lifting the ladders 24 and 25 out of the wagon, then separating the side members 18 70 from their supporting-standards by removing the bolts 23, the standards may be raised and the wagon be left in the condition shown in Fig. 6, when it can be used as an ordinary farm-wagon for hauling grain, lumber, &c. 75 The legs 21 can then be introduced into the guides or grooves 14 until the beveled ends 32 of the body-pieces strike the similarly-shaped upper ends 33 of the strips 13, the side members 18 then forming the sides of the 80 stock-rack. When the sides are thus mounted, they are vertically disposed, and they are held firmly in position by the bolts 23, which, it will be remembered, are employed for holding the standards or cross-bars 15 in place 85 when the wagon is used for carrying hay.

The wagon when used for carrying stock has front and rear gates, as 35, vertically slideable in guide-grooves, as 36, in the inner (at this time) sides of the side members 18. These 90 guide-grooves are conveniently formed by suitably-arranged strips 37, secured to the body members 19. The addition of the gates between the slatted sides forms a single large compartment.

It is sometimes necessary to separate the stock, and for this purpose I provide a central gate, as 38, slideable in guide-grooves 39 in the side members 18 and wagon-box, respectively, these grooves, like certain others, being 100 formed by adjacent strips vertically disposed and secured to the respective parts. The middle gate not only divides the stock-rack into compartments, but materially strengthens the wagon at its middle, a portion that is frequently subjected to considerable transverse strain. 105

By covering one or both of the compartments poultry may be safely carried.

To further strengthen the rack portion of 110 the wagon, I may use the tie-bolts 40, having the usual spring-pins, said bolts extending crosswise of the wagon and passing through the slotted side members 18 thereof.

By separating all the removable parts from 115 the wagon-box 12 and inserting the outer ends of the posts 50 in the end grooves 14 I provide a wagon especially adapted for carrying corn-fodder or lumber. The box 12 can be loaded with the stalks or wood lengthwise 120 thereof until the wagon is filled, after which the stalks or wood can be placed crosswise of the wagon, the upright posts preventing them from rolling off.

The wagon is not only strong and light, but 125 it may be readily changed from one of its characters to another by one man in a short space of time, this operation with existing types of vehicles of this kind requiring the services of two or more men and generally 130 consuming much time.

The superfluous parts when not in use can

be carried in the wagon-box and the wagon can be changed in a very short space of time to any one of its uses.

Having described the invention, what I claim is—

1. In a wagon, a box having guides in its sides, and notches in said sides alined with the guides, cross-bars removably fitted in said notches, and side members detachably connected to the cross-bars, having legs adapted to be fitted into said guides when the cross-bars are removed.

2. In a wagon, a box having guides in its sides, said sides having notches alined with the guides, cross-bars removably fitted in said notches having squared ends fitted against the inner face of the sides of the box, and side members detachably connected to the cross-bars, having legs adapted to be received by said guides when the cross-bars are removed.

3. In a wagon, a box having guides on its sides and notches in said sides, cross-bars removably fitted in said notches, side members detachably connected to the cross-bars, having legs adapted to be fitted into said guides when the cross-bars are removed, and front and rear ladders held in place by the adjacent cross-bars.

4. In a wagon, a box having guides on its sides and notches in said sides, cross-bars removably fitted in said notches, side members detachably connected to the cross-bars, having legs adapted to be fitted into said guides when the cross-bars are removed, and front and rear ladders having projections to engage under adjacent cross-bars, one of the ladders having a series of holes and a pin to enter one of said holes.

5. In a wagon, a box having guides in its opposite sides and notches alined with said guides, cross-bars detachably received by said notches, side members having legs to fit into said guides when the cross-bars are removed therefrom, and loops upon the cross-bars to receive said legs.

6. In a wagon a box having strips arranged vertically in parallelism on its opposite sides to form guide-grooves, said sides also having notches, standards or cross-bars to fit in said

notches, side members having legs to fit in said guide-grooves; and means for detachably securing the side members to said standards or cross-bars.

7. In a wagon a box having strips arranged vertically in parallelism on its opposite sides to form guide-grooves, said sides also having notches; standards or cross-bars to fit in said notches, side members having legs to fit in said guide-grooves; means for detachably securing the side members to said standards or cross-bars, additional strips on the sides to coöperate with said other strips to form ladder-receiving grooves, and ladders fitted in said last-mentioned grooves, and held in place by adjacent cross-bars.

8. In a wagon, a box having notches in its sides and strips secured to said sides, arranged to form guides, the strips being beveled at their upper ends, cross-bars adapted to removably fit in said notches, and side members having body-pieces beveled to correspond with said strips, said body-pieces having legs to enter said guides.

9. In a wagon, a box having guides on its sides, cross-bars or standards removably supported by said sides, and slotted side members removably supported by said cross-bars or standards, and having legs to be fitted in said guides when the cross-bars or standards are removed.

10. In a wagon, a box having guides in its opposite sides, slatted side members having legs fitted in said guides, and gates fitted between said slatted side members.

11. In a wagon, a box, side members detachably connected with the box, guides at the opposite ends of the side members, end-gates fitted in said guides, coöoperating strips secured to the side members and the sides of the box to form additional guides, and a third gate to enter said last-mentioned guides.

In testimony whereof I have hereunto set my hand in presence of two subscribing witnesses.

CHARLES A. BABB.
